UNITED STATES PATENT OFFICE.

CHRISTOPHER C. BOYKIN, OF BLACKSBURG, VIRGINIA.

BILL-FILE.

SPECIFICATION forming part of Letters Patent No. 550,435, dated November 26, 1895.

Application filed November 17, 1894. Serial No. 529,155. (No model.)

To all whom it may concern:

Be it known that I, CHRISTOPHER C. BOYKIN, a citizen of the United States, residing at Blacksburg, in the county of Montgomery and State of Virginia, have invented a new and useful Bill-File, of which the following is a specification.

This invention relates to that general class of bill-files wherein a rod or wire is provided and made capable of having the bills successively strung thereon, and it is specifically related to that class in which the rod or wire is associated with means for perforating the bills, so that they may be more easily and regularly attached to the file, and so that they will not be unnecessarily torn or mutilated in effecting such attachment.

This invention consists in certain novel features and details of construction and arrangement of parts, as hereinafter fully described, illustrated in the drawings, and finally embodied in the claims.

Figure 1 represents a perspective view of a bill-file embodying the essential features of my invention and showing a series of bills thereon; Fig. 2, a longitudinal section taken through one of the rods; Fig. 3, a horizontal section taken through the base-plate and showing the means for holding the rods in place, and Fig. 4 a detail perspective of one of the terminals of the filing-rods, showing the cutting devices thereof.

Two perforating devices are embodied in my invention in consequence of the use of two filing-rods, as will be understood, and the reference-numeral 1 indicates the said filing-rods, which comprise vertically-extending portions *a* bent at their upper ends to form the downwardly-extending portions *b*, the extremities of which terminate in cutting devices, as will be described hereinafter. The filing-rods are each secured to the base-plate 2, which is formed, preferably, of wood and substantially rectangular in shape.

The securing of the filing-rods is effected by means of the arms 3, which are formed one at each side of the base-plate by slotting the same, as shown. The slots are one for each arm and are located at each side of the base-plate, they being extended first inwardly and transversely from the outer sides or edges thereof and thence rearwardly and longi-

tudinally. This forms two spring-arms which lie inward of the edges or sides of the base-plate and which are integral therewith, this fact being responsible for a spring tendency which said arms have to extend in alignment with the sides of the base-plate.

4 indicates a bolt which is passed horizontally and transversely through the base-plate 60 and through the free ends of the arms 3, the purpose of said bolt being to draw the arms inwardly and toward the center of the base-plate, causing them to move against their tendency and to decrease the width of the 65 respective slots which form them. By these means the lower ends of the filing-rods 1 may be respectively clamped between the arms 3 and the adjacent portions of the slots which form the arms, whereby the filing-rods are 70 held in proper position as securely as may be desired and with the capability of being removed when the exigencies of the occasion may require.

5 indicates the bill-receiving plate aforesaid, which is formed of rigid sheet metal and substantially rectangular in shape, and which has its front edge turned up, as shown, so as to hold the papers raised above the remainder of the plate. This plate is of such 80 a size that it will occupy the major portion of the base-plate forward of the free ends of the arms 3, and is secured to the base-plate so as to be capable of a limited movement thereon by means of the headed pins 6, which 85 are two in number, and which are driven into the base-plate at points just forward of the arms 3, and one near each side of the base-plate. These pins pass through openings in the rear edge of the plate. The openings in the bill-receiving plate are slightly 90 larger than the pins 6, to the end that the plate may have the requisite movement thereon, and this movement consists in a slight vertical swing, making the plate capable of 95 moving up to and above the extremities of the downwardly-extending portions *b* of the filing-rods. Formed by striking up from the metal composing the plate 5, and one at each side thereof, are the lugs 7, which are consequently two in number and which are transversely aligned with each other. The formation of the lugs 7 will decrease to a slight degree the width of the plate 5 rearward of said

lugs. This decrease in the width of the plate will not, however, affect the substance thereof, all of which will be understood, and it might further be added that these lugs could 5 be formed by other means, such as casting integral or by riveting them in place, all of which will be understood without further description.

Formed in the bill-receiving plate 5, and 10 at points directly under the extremities of the downwardly-extending portions *b* of the filing-rods 1 are the circular openings 8, which are two in number and which are provided for co-operation with the perforating 15 devices, as will now be described. Rigidly secured to, preferably by soldering, the extremities of the downwardly-extending portions *b* of the filing-rods are the tubes 9, which are provided to cut the paper and which have 20 their lower ends shaped with two transversely-aligned points 10, forming substantially a V-shaped indentation in the lower ends of the tubes. The lower ends of the parts *b* of the filing-rods are similarly formed, 25 as indicated at 10^a, so as to conform to the shape of the tubes 9, and the tubes are projected slightly out from the rods so as to leave their cutting-edges free to operate. These tubes are of such a size that they will be 30 capable of passing through the openings 8 of the receiving-plate, and they are greater in diameter than the diameter of the filing-rods, which of course is essential, owing to the fact that the tubes embrace or receive the filing rods.

The free or forward edge of the plate 5 is formed with a bead 12 thereon, which adds to the appearance of the device, and which is provided to make the manipulation of the 40 plate easy. This is so by reason of the fact that the bead furnishes convenient means for grasping the plate, as is necessary in the operation thereof.

That portion of each filing-rod which carries 45 the respective cutting-tubes is bent forwardly and longitudinally so as to extend in a line approximately conforming to the arc of the circle described by the plate 5 when it swings in its operation. Thus as the plate 5 is moved 50 upward the parts are so gaged that the openings 8 will pass over the cutting-tubes, or rather so that the cutting-tubes will pass through the openings, and it is this operation by which the perforation of the paper is effected.

It will be observed that as the plate 5 is raised the points 10 of the cutting-tubes will first pierce the paper and that as the raising of the plate is continued the points will pass 60 into and through the paper, thereby completely severing a circular disk at each cutting-tube. As the disk is severed at each cutting-tube it is first forced up between the points of the same, but the elasticity of the 65 paper immediately reacts against the points and causes the disks to be expelled almost instantly after they have been lodged between

the points. The return of the plate 5 also assists in the removal of the disks, which, together with the fact that the rods 1 extend 70 down into the tubes very nearly to their cutting edges, makes it absolutely impossible for the perforating apparatus to be clogged with paper.

In the use of my invention the bills to be 75 filed are placed face downward upon the receiving-plate and with their front edges in engagement with the lugs 7 of said plate. By these means the position of the paper may be gaged. When this has been done, the plate 5 80 should be moved upwardly until the cutting-tubes 9 pass through the respective openings 8, whereupon the paper will be perforated and strung upon the downwardly-extending portions *b* of the filing-rods. The operation is 85 completed by releasing the plate 5 and allowing the same to return by gravity to its normal position, and by moving the bill up the parts *b* of the filing-rods around the bends thereof and finally down the vertically-extending portions *a* thereof, where they may 90 rest upon the base-plate, as shown in Fig. 1.

The lower ends of the vertical portions *a* of the filing-rods are slightly reduced in size and perforated to form the eyes 13, the purpose of which is to permit securing a cord or wire to the lower end of each filing-rod, so that the bills of the latter may be readily transferred to the cords or wires for permanent filing or for storing away. This removal 100 of the bills is effected by loosening the bolt 4, which permits the arms 3 to move outwardly and which makes it possible to easily remove the filing-rods. When this removal of the rods has been effected, the wires or cords 105 aforesaid may be connected to the eyes 13 and the bills transferred, as explained. It is also possible to remove the filed bills by passing a wire up through the openings in the bills when they are in place and then removing 110 the filing rods and bills by way of the slots in the base-plate 2. This avoids the possibility of separating the bills and destroying their relative arrangement.

It will be observed that owing to the construction of my device it will be easy to refer to the bills filed thereon without necessitating their removal, all of which will be understood. The invention is particularly adapted 115 for the filing of druggists' prescriptions, but 120 is, of course, applicable to all other mercantile purposes and indeed to all uses which entail the filing of papers of any kind.

Changes in the form, proportion, and the minor details of construction may be resorted 125 to without departing from the principle or sacrificing any of the advantages of this invention.

Having described the invention, I claim—

1. A bill file comprising in its construction 130 a base plate having an arm formed integral therewith and by cutting a slot in the base plate, the arm having a spring tendency whereby the slot is held open when said tend-

- ency is not overcome, a filing rod having its lower end inserted in said slot, and a bolt passing through the arm and into the main portion of the plate, whereby the filing rod 5 may be removably clamped in place, substantially as described.
2. A bill file comprising in its construction a base plate rectangular in form and having in opposite sides thereof two slots which extend inwardly and thence longitudinally at right angles to the sides, whereby two arms are formed integral with the base plate, a bolt passing horizontally through the arms and base plate, whereby the arms may be drawn inwardly, and a filing rod for each slot, each rod having its lower end arranged in one of said slots and secured in place by clamping the corresponding arm against it, substantially as described.
- 20 3. In a bill file, a base plate, a filing rod secured thereto and extending upwardly therefrom and thence downwardly so as to have two parallel portions, the free end of the filing rod having a cutting edge thereon, and a
- spring plate mounted on the base plate and 25 having an opening therein capable of receiving the free end of the filing rod as the plate is moved into engagement therewith, substantially as described.
4. A perforating device consisting of a rod 30 having a V-shaped notch in its end, a cutting tube affixed to and surrounding said end and projecting slightly beyond the same and also having a V-shaped notch conforming to the notch in the rod, whereby the diameter of the 35 cutting end of the filing rod is greater than its shank, and a plate having an opening therein and capable of moving into engagement with the cutting tube and of having the same passed through its opening, substantially as described.

In testimony that I claim the foregoing as my own I have hereto affixed my signature in the presence of two witnesses.

CHRISTOPHER C. BOYKIN.
